BASEBALL AND SIMILAR GAME

Fielding B. Simmons, Ventura, Calif.

Application November 7, 1938, Serial No. 239,295

11 Claims. (Cl. 273—89)

My invention relates to baseball and similar games, such as cricket.

One of the principal objects of this invention is to provide a game of this class which will simulate, as nearly as possible, some of the varying undetermined events and features of a baseball and other games.

An important object also is the provision of a competitive game of this class in which the opposite sides are controlled by different players, and controlled and operated secretly.

A particular object is the provision of a pitcher and batter each of which may be controlled by one of the players to direct the ball or game member in different directions and at different speeds.

An object of this invention also is the provision of a catcher which is manipulated by the player controlling the pitcher.

20 A further important object of this invention is the provision, of simple and novel means for determining whether a certain pitched ball is a ball or strike, and also for registering the same.

25 A further object also is the provision of a game of the class which is simple and economical of construction.

With these and other objects in view, as will appear hereinafter, I have devised a game apparatus having certain novel features of construction, combination, and arrangement of parts and portions, as will be hereinafter described in detail and particularly set forth in the appended claims, reference being had to the accompanying drawings and to the characters of reference 30 thereon, which form a part of this application, in which:

Fig. 1 is a plan view of a baseball game embodying my invention, certain portions being shown in moved positions by dotted lines;

40 Fig. 2 is an elevation taken from the pitcher control end;

Fig. 3 is an elevation taken from the batter control end;

Fig. 4 is an enlarged fragmentary plan view 45 showing the pitcher operating means;

Fig. 5 is a fragmentary elevation thereof;

Fig. 6 is an enlarged fragmentary plan view of the batter operating means;

Fig. 7 is a fragmentary elevation thereof;

50 Fig. 8 is a diagrammatic view of the strike and ball registering means; and,

Fig. 9 is a fragmentary elevation thereof.

Referring to the drawings, 1 designates the table or game board on the upper side of which 55 is painted or otherwise represented the field of

play consisting of the baseball diamond 1a, and on which are also shown various playing members, and at the underside of which are the actuating mechanisms for the various playing members or devices.

At the pitcher's box 1b is located a spindle or pin 11, which represents the pitcher and which extends above the field of play and is rotatable on a vertical axis. On the upper end of the spindle is attached a swingable arm 12. This 10 arm is recessed for temporarily locating a ball A while the arm is swung. This arm is preferable readily detachable so that it may be readily replaced by others.

Opposite the home plate 1c is located a second 15 spindle or pin 21, which represents the batter and also extends above the field of play and is rotatable on a vertical axis. On the upper end of this spindle is attached a swingable arm 22 which simulates a bat. This bat is also preferable 20 readily detachable so that bats may be readily interchanged.

Although in the ordinary baseball game the 25 umpire is located behind the catcher, in this instance, the means for determining whether the pitched ball is a "strike" or "ball" is located between the bat or batter 22 and the catcher 31. This ball determining means, as seen above the game board or playing field, consists of a strike 30 registering bar 41, arranged transversely to the line between the pitcher and catcher, and ball registering bar 42, located at the opposite sides of the strike-bar and in alignment therewith. These bars 41 and 42 are located at the upper ends or form the cross portions of U-shaped 35 loops, the legs of which extend downwardly through slots 1d in the game board. These bars may be easily forced backwardly, and in their extreme rearward positions are flush with the top of the game board and allow the ball to 40 continue its progress.

On the field of play are a plurality of movable 45 pockets 51, 52, 53, 54, 55, 56, and 57, all of which have downwardly extending legs which are arranged to rest and to be guided in slots 1e located respectively at the places usually occupied by the infielders, that is, the first baseman, second baseman, third baseman, shortstop, and the 50 outfielders, that is, the right fielder, left fielder, and center fielder. The slots for the infielders are arranged on the base line, while those of the outfielders are also arranged in straight lines but the first two are substantially parallel respectively to the nearest base lines, and the cen- 55

ter field slot extends transversely across the rear of the field of play.

The action of the pitcher 12 is controlled by three members 13, 14, and 15 located at the end 11 of the field of play or game board, while the action of the batter 22 is controlled by three similar members 23, 24, and 25 at the opposite end 11.

On the pitcher spindle 11, below the game board, is a quadrant 16 on or around which is wound a spring member or rubber band 17, one end being secured to the quadrant and the other end of which is fastened to the control member 13, which is a bar for adjusting the tension for variously swinging the pitcher. The end of the bar, extending beyond the game board, or the enclosure or box 2 surrounding the same, has steps or shoulders 13^a, ^b, and ^c which may engage the outer side of the enclosure 2 for fixing the position of the bar 13, and thereby limiting the tension or rotating force on the pitcher spindle 11, and thereby determining the speed of the pitched ball. The quadrant 16 has a catch or shoulder 16^a which is normally engaged by the inner end of the control member 14, which is a trigger. This trigger or trigger rod may have a lever 14^a at the outer end, which may be merely depressed for withdrawing the trigger rod from engagement with the shoulder 16^a, allowing the spindle to be rotated by the tension member 17.

The control member 15 is a variable stop in the form of a longitudinally adjustable rod. The inner end serves as a stop to check the rotation of the spindle and may be engaged by one of a plurality of stops 18^a, ^b, and ^c on the quadrant 18, also provided on the inner end of the spindle. These stops are located at different radial distances from the rotating axis, and also circumferentially spaced from each other. The outer end of the control rod also has steps or shoulders 15^a, ^b, and ^c which may be positioned against the inner side of the enclosure for locating the member 15 and determining beforehand the limit of rotation of the spindle 11, which determines substantially the direction in which the ball is thrown or pitched.

On the batter spindle 21, below the game board, are also two quadrants 26 and 28. On or around the former is wound a spring member or rubber band 27, one end of which is fastened to the quadrant and the other end to the inner end of the control member 23, which is the lever for adjusting the tension for variously swinging the batter. This lever is pivoted intermediate its ends, and the end of the lever, extending beyond the enclosure 2, may be shifted into one of several angular positions, and into a corresponding recess 2^a, ^b, and ^c in the wall of the enclosure, for holding the lever in said shifted position. Thereby the tension or rotating force on the batter spindle is predetermined, determining the impact on the pitched ball. The quadrant 26 also has a catch or shoulder 26^a which is normally engaged by the inner end of the control member or trigger 24. The trigger is shifted laterally to trip the quadrant and release the bat.

The control member 25 is a variable stop for the batter, and is a lever pivoted intermediate its ends. The inner end serves as a stop to stop the rotation of the batter spindle 21 in definite positions. This is effected by the engagement of said end by one of a plurality of stops 28^a, ^b, and ^c on the quadrant 28. These stops are located at different radial distances from the rotating axis 75 of the batter spindle, and are also circumferen-

tially spaced from each other. The control lever 25 may also be shifted angularly so that the inner end may be engaged by the stops or shoulders 28^a, ^b, or ^c. These angular positions may be determined by recesses 2^d, ^e, and ^f in the wall of the enclosure 2. The position of the control lever 25 determines beforehand the limit of rotation of the spindle 21, and thereby determines to a large extent the direction of the path of the ball when struck.

The catcher 31 is in the form of a basket for receiving the pitched ball A when not struck by the batter. The catcher basket has legs which extend downwardly through an arcuate slot 1^k in the game board, and may be shifted from one end of the slot to the other in an attempt to catch the pitched ball. Such shifting of the catcher may be effected by interlocking levers 32 and 33, both of which are pivoted intermediate their ends. The slot 1^k is preferably arranged on an arc with the pivotal axis of the lever 32 as a center. One end of the lever 33 extends outwardly through a slot in the enclosure at the same end of the field of play as the pitcher controls. In order to move the catcher basket 31, the outer end of the lever 33 is moved in the same direction as the former.

The supporting legs of the strike registering bar 41 and the ball registering bars 42, of the ball determining means, are pivotally supported intermediate their ends below the game board. One of the supporting legs of each bar is operatively connected at its lower end to a counter, such as by electrical connections. The strikes are registered on a counter 43, and the balls on a counter 44. The counters are controlled by electric circuits 45 and 46 when switches 45^a and 46^a are closed. The switch 45^a may be directly connected to the lower end of one of the legs supporting the strike bar 41. When a ball A strikes the strike bar 41 the carrying frame thereof is tilted, closing the switch and actuating the counter in any suitable manner, not shown.

The frames, carrying the ball registering bars 42, are preferably connected, by a rod 42^a, to operate as a unit. One of the legs of the frame for carrying the bars 42 is spaced from but arranged to engage the end of a plunger 47 which is connected to close the switch 46^a when the plunger is engaged by the supporting leg of the bars 42. It may happen that the pitched ball may be directed between the strike and the ball bars, and engage and move both the bar 41 and one of the bars 42. In order to avoid operation of both counters, I have provided a bell crank lever 48, one arm 48^a of which is engaged by one of the supporting legs for the bar 41, and the arm 48^b of which engages the side of the free end of the plunger 47, for forcing it to one side before it can be engaged by the supporting leg of the bars 42. The plunger 47 is resiliently held, by a spring 49, in a guide 50, and will readily yield to the action of the lever 48. If, however, the bar 42 is moved first, an offset or side lug at the outer end of the plunger 47 prevents the latter from being shifted laterally. The arm 48^b is slightly flexible so as to yield when the plunger 47 is locked by the supporting leg of the bar 42.

If it is desired to register a ball or strike manually, switches 45^b and 46^b may be separately operated. Any desired and conventional means, not shown, for clearing the counters for the next batter may be provided.

The pocket or baskets 51, 52, 53, 54, 55, 56, 75

and 51, representing the backfield players, are U-shaped, and may be made of wire with the legs of each extending through the slots 1° below the game board. At the end of the field 5 of play, at which the pitcher controls are located, are suitable control devices, shown as handwheels 61, 62, 63, 64, 65, 66, and 67 for shifting the pockets or baskets, representing the backfield players, to catch or net the ball A which 10 may be struck by the batter. At the opposite ends of each slot, at the underside of the game board, are sheaves 58. Around the sheaves of each slot and around the corresponding handwheel extends a cord, cable, or tape 59 for moving said cord, or the like, by the movement of the corresponding handwheel. The legs of the pockets or baskets which extend through the slots are secured to the portion of the cord below the particular slot. The cords are crossed 15 20 as shown so that the pockets or baskets are moved in the direction of movement of the handwheels. The handwheels are also arranged to correspond as nearly as possible to the pocket or basket of the outfielder it represents.

25 Though I have shown and described a particular construction, combination, and arrangement of parts and portions, and particular means of operation and control of the several devices and features of my game apparatus, I 30 do not wish to be limited to the same, but decide to include in the scope of my invention, the construction, combination, and arrangement substantially as set forth in the appended claims.

I claim:

35 1. In a game of the class described, a field of play having a movable pitcher therein, a trigger at one end of the field for holding the pitcher against movement, and for manually releasing the pitcher to allow rotation thereof, manually 40 varying resilient means for causing varying speeds of rotation of said pitcher, and manually controlled stop means at the same end of said field for secretly causing the movement of the pitcher to stop in various positions.

45 2. In a game of the class described, a field of play having a movable pitcher therein, a trigger at one end of the field for holding the pitcher temporarily in a fixed position, and for manually releasing the pitcher to allow movement 50 thereof, resilient means for causing varying speeds of movement of said pitcher from said fixed position, and manual means at said end of the field for increasing and decreasing at will the tension of the resilient means.

55 3. In a game of the class described, a field of play having a movable batter thereon, a trigger at one end of the field of play for holding the batter temporarily in a fixed position and for manually releasing the batter to allow movement 60 thereof, resilient means for causing varying speeds of movement of said batter from said fixed position, and manual means at said end of the field for increasing and decreasing at will the tension of the resilient means.

65 4. In a game of the class described, a field of play having a movable batter thereon, a trigger at one end of the field of play for holding the batter against movement and for manually releasing the batter to allow movement thereof, a 70 manually varying resilient means for causing varying speeds of movement of said batter, and manually controlled stop means at the same end of said field for secretly causing the movement of the batter to stop in various positions.

75 5. In a game of the class described, a field of

play having a movable batter thereon, a trigger at one end of the field of play for holding the batter against movement and for manually releasing the batter to allow movement thereof, means for causing movement of the batter when released by the trigger, and separate manually controlled stop means at the same end of said field for secretly causing the movement of the batter to stop in various positions. 5

6. In a game of the class described, a field of 10 play, a movable pitcher and a movable batter thereon, a trigger at one end of the field of play for holding the pitcher against movement and for manually releasing the pitcher to allow movement thereof, a second trigger at the opposite end for holding the batter against movement and for manually releasing the batter to allow movement thereof, and separate manually varying resilient means for causing varying speeds of movement of the pitcher and batter, 20 each of the resilient means having control means located at the end of the field of play at which the corresponding trigger is located.

7. In a game of the class described, a field of play, a movable pitcher and a movable batter 25 thereon, a trigger at one end of the field of play for holding the pitcher against movement and for manually releasing the pitcher to allow movement thereof, a second trigger at the opposite end for holding the batter against movement and 30 for manually releasing the batter to allow movement thereof, resilient means for causing movement of the pitcher and batter when their respective triggers are released, and separate manually controlled stop means for the pitcher and 35 the batter, each stop means being located at the end of the field of play at which the corresponding trigger is located.

8. In a game of the class described, a field of 40 play having a pitcher and a batter representation, means for ejecting an object from the pitcher toward the batter representation, a tiltable strike-bar located in line with the pitcher and batter representation and behind the latter, said strike-bar being tiltable backwardly from the 45 batter representation by the object when the same is ejected past the batter representation, a counter, and means operatively connecting said counter to said bar.

9. In a game of the class described, a field of 50 play having a pitcher and a batter representation, means for ejecting an object from the pitcher toward the batter representation, a tiltable strike-bar located in line with the pitcher and batter representation and behind the latter, a 55 counter, means operatively connecting said counter to said bar, tiltable ball-bars located at the opposite sides and in alignment with the strike-bar, said bars being tiltable backwardly 60 from the batter representation by the object when the same is ejected past the batter representation, a second counter, and means operatively connecting the second counter to said ball-bars.

10. In a game of the class described, a field of 65 play, a movable pitcher and a movable batter thereon, a trigger for holding the pitcher temporarily in a fixed position and for manually releasing the same to allow movement thereof, a second trigger for holding the batter temporarily 70 in a fixed position and for manually releasing the batter to allow movement of the latter, separate resilient means for causing varying speeds of movement of the pitcher and the batter, and separate manual means for increasing and de- 75

creasing at will the tension of both of the resilient means.

11. In a game of the class described, a field of play, a movable pitcher and a movable batter thereon, a trigger for holding the pitcher against movement and for manually releasing the pitcher to allow movement thereof, a second trigger for manually releasing a batter to allow move-

ment of the latter, resilient means for causing movement of the pitcher and batter when the respective triggers are released, and separate manually controlled stop means for the pitcher and the batter for variously stopping the movement of each. 15

FIELDING B. SIMMONS.
